WILLIS J. MURDOCK, OF AURORA, AND EDGAR E. LUNGEN, OF JOLIET, ILLINOIS, AND OWEN B. EVANS, OF PHILADELPHIA, PENNSYLVANIA, ASSIGNEES, BY MESNE ASSIGNMENTS, TO PIER PROCESS CORPORATION, OF AURORA, ILLINOIS, A CORPORATION OF ILLINOIS.

PROCESS FOR MANUFACTURE OF COMBUSTIBLE GAS.

Application filed September 23, 1924. Serial No. 739,282.

This invention relates to improvements in process for manufacture of combustible gas.

In the manufacture of combustible gas, such as blue or carbureted water gas, or producer gas, from solid fuel, one of the main operations is the blasting which takes place in the generator, by which the bed of fuel is gradually and progressively reduced and heated to incandescence in order to permit the necessary chemical reactions taking place in the generator.

Gas generating fuels as received at the gas producer are ordinarily composed of mixed sizes, and as the fuel is charged into the usual cylindrical generator, it is a well known fact that the finer or smaller particles of the fuel, sometimes referred to as the "fines", tend to concentrate in the center of the generator, and the larger or coarser particles tend to gravitate or roll towards the confining walls, that is, there is a natural tendency of solid fuels to more or less segregate into an outer mass of larger or coarser particles, and an inner or central core or mass of finer or smaller particles. Furthermore, when the fuel is charged into the generator from the top, as customary, there is a natural tendency of the fuel to crown at the center on the top of the fuel bed.

Experience has demonstrated that where the fuel in the generator is permitted to follow its normal course in the manner indicated in the preceding paragraph, there is a very noticeable variation in the degrees of permeability of the fuel bed to the passage of air or steam, or air and steam blasts up through the supporting grate and through the fuel bed, or in the reverse direction, the outer portion of the mass adjacent the retaining walls of the generator offering a very much less resistance to the passage of the blasts therethrough than the central portion or mass, with the result, in actual practice, that the outer portion of the fuel bed for a more or less determinable definite distance from the wall, depending upon the particular characteristic of the fuel being used, becomes activated or what is known as an "active area", whereas the central mass

of the fuel bed becomes what is known as an "inactive area".

As the fuel is consumed in an ordinary generator of circular cross section, and new charges added the entire mass descends gradually and slowly to the grate. When a fuel low in volatile matter is used, such as anthracite coal or coke, it passes from the upper zone of what is called "green" or comparatively cold fuel to the next lower zone of incandescent fuel during the distillation, carbonization and processing thereof, and finally from the incandescent zone down to the last zone of spent fuel or ashes resting upon the grate. When fuel high in volatile matter is used, such as bituminous coal, there is an additional zone, commonly called the "plastic zone", which forms above the incandescent zone due to the driving off of the larger amounts of volatile matter therefrom in the distillation and processing thereof to the coke condition necessary to obtain a water gas reaction. During this gradual descent of the fuel through the generator, the outer portions of the fuel, in contact with or closely adjacent to the retaining walls of the generator, are appreciably retarded in their movements because of the friction between those portions of the fuel and the walls, whereas the center portion of the mass of fuel is free to settle more quickly, thus producing a differential settling action, which further tends to compact or solidify the center portion of the fuel and loosen or render more permeable the outer peripheral portions of the fuel. The settling action described further tends to increase the difference in permeability to the blasts of air and steam between that of the outermost portions and that of the center portions of the fuel bed.

Another factor still further tending to increase the difference in permeability between the outermost portions, and the inner portions of the fuel bed, when bituminous coal is used in the generator, is that which results from the formation under heat, of the plastic zone referred to, which during the progression of combustion envelops the central inert mass, so as to completely cut off the same from blasting and carbonization.

This condition is due to the difference in permeability referred to, causing a distinct and well known tendency of the air, when introduced below the grate, to select a passage up through the generator between the refractory wall and the fuel itself, rather than through the body of the fuel, resulting in much more rapid combustion and higher temperatures being evolved in this portion 5 of the fire. This condition is observable in connection with all kinds of generator fuels, but in the case of a soft coal fire is accentuated because there is a shrinkage of the fuel away from the refractory wall of the 10 generator during the process of carbonization, giving a still freer passage to the air. The high degree of heat which is thus evolved about the periphery of the fire progresses through the bed of fuel horizontally 15 relatively to the refractory walls of the generator, and to a known limited distance from such walls, and this portion of the fuel rapidly reaches a state of incandescence during the blast, ready for the water gas reaction, for a horizontal width of only from 18 to 24 inches inwardly from the wall of the 20 generator, which is an appreciable distance from the center thereof. This action causes the formation, during the various stages of 25 progression of the active portion of the fuel, of the sticky plastic zone of partially coked fuel immediately in advance of the incandescent area throughout its extent, and since such area extends inwardly from the wall of 30 the generator only approximately from 18 to 24 inches, the plastic formation completely surrounds the inner mass of the fuel bed. Inside of this plastic envelop there will be 35 found fuel which is not completely distilled or carbonized to a depth reaching to, or almost to the grate, which is impervious to the blast, and the consequence is that this inert mass is almost entirely inactive and uncarbonized. 40

The result of the combination of all or some of the foregoing factors normally tending to take place in a generator of the usual character with the usual method of manufacture where the entire mass of fuel 45 is supported on a grate of the usual character, is to produce an outer mass or area, which is relatively very active and subject to rapid combustion, and an inner central portion or mass which is inactive and in which little or no combustion takes place. Furthermore, where a very active area is 50 developed, so-called "weak spots" are produced in those portions of the fuel bed with the result that "channelling" ensues, thus 55 permitting a relatively excessive flow of air in and adjacent the channels, more rapid burning or consumption of the adjacent fuel, and an increased flow of air, steam and gas. In such condition of unstable equilibrium, 60 the channeling action becomes progressive 65

and may, and often does, reach a point such that all the blast is practically concentrated in one path through the body of fuel and this, in turn, permits the blast to assume a very high velocity in its passage through the fuel 70 and to carry with it portions of solid fuel over into the fixing chamber, thus causing frequent clogging of the latter, and necessitating shutting down to clean it out, with consequent loss of time and use of the 75 apparatus.

The foregoing condition occurs with all solid generating fuels in general, and is particularly accentuated when bituminous coal is used, due to its immobile and sticky 80 character when partially coked, causing it to form the plastic zone which is not only impervious to blasting as before stated, but will not of itself, fill the holes or channels which may be formed, and it becomes necessary to bar the fuel bed frequently. 85

Objects of our invention, therefore, are to provide improvements in the process of manufacturing a combustible gas from solid fuel, which will obviate the disadvantageous conditions hereinbefore described; to so carry out the action in the generator as to insure a bed of fuel of practically or substantially uniform permeability to the blast products and render the entire body 90 substantially uniformly active; to increase the activated area of the fuel bed; to eliminate the formation of the inactive or more or less impermeable portions of the fuel bed; and, in general, to materially increase the efficiency and economy of operation of the 95 steps of the process in the generator necessary in the manufacture of a combustible gas. 100

Our invention, considered from some of its broader aspects, consists in so disposing or dispersing the conglomerate mass of solid fuel as it is charged into the generator and in its passage through the generator, that every portion of the fuel bed will be within 105 an "active" area with respect to a radiating wall of the generator; in preventing the initiation of the formation of a compacted relatively impermeable portion at any point in the fuel bed; in increasing the amount of radiating wall bounding area for the fuel relative to the volume of the fuel contained within the generator; in providing a refractory body extending well into or through the zone of loose or green fuel to act as a 110 core to replace what would be the normally formed inert and inactive portions of the fuel bed; in cooling such body to prevent injury thereto from excessive heat; in so distributing the fuel while subjected to action in the generator that the distance between any two walls transversely of the fuel bed does not exceed twice the width of the known or determinable active area of the 115 fuel with respect to a wall; and in permit- 120

ting the blasts of air and steam to enter the fuel bed through the grate with uniformity throughout the grate supported area of the fuel while the body of the fuel is 5 arranged as indicated in the preceding.

In the drawings forming a part of this specification, Fig. 1 illustrates a more or less diagrammatic view indicating a vertical, diametrical section of a generator of cylindrical form adapted for the carrying out of our improved process, and Fig. 2 is a transverse sectional view of the generator shown 10 in Fig. 1.

In said drawing, the generator proper is 15 indicated at 2, the same preferably being of cylindrical formation as generally employed, and preferably lined on the interior of the outer confining wall with refractory material. Said generator is preferably provided 20 with a horizontally extended grate 3, which may be of usual construction and disposed above the bottom of the generator proper so as to leave an ash pit 4 from which some of the ashes may be removed through a suitable 25 ash pit door 5. Clinker doors of any desirable construction are indicated conventionally at 6. As customary in a generator of this character for producing carbureted water gas, the generator is provided with 30 an offtake passage 7, near the top, the gases being conducted through a suitable pipe 8 having the usual interconnected valves 9 and 10. The fuel, as customary, is charged through the top opening 11.

35 For the purpose of carrying out our invention, in one manner, in the type of generator shown we provide a centrally disposed pier or cone indicated broadly by the reference character A, said pier or cone A 40 preferably being of circular cross section and disposed centrally of, and supported upon the grate 3. Such pier may be of any desired construction, that is, either hollow or solid, or of a suitable built up construction 45 where intended for application to a generator already in use, and is preferably composed of suitable refractory material. The topmost portion of the pier is preferably cone shaped, as indicated at 12, so as 50 to facilitate the uniform distribution of the fuel all around the generator as the fuel is charged through the top opening 11. In actual practice, and this is an important consideration in our invention, the pier will 55 be extended well up into the green or loose zone of the fuel, and preferably substantially level with the offtake opening 7. In this manner, the beginning or initiation of the formation of a central inactive cone in the 60 body of the fuel at any stage of distillation, carbonization or processing thereof is prevented. Furthermore the amount of fines in the fuel which would normally tend to concentrate and compact in the center 65 portion of the generator occupied by the

pier A, will be distributed in an annulus of much greater radius, and thoroughly intermingle with the larger portions of the conglomerate mass of fuel.

Although the pier A may be of any solid 70 construction if desired, it is preferably provided with an interior chamber 13, extending from the bottom of the pier to a point adjacent the top thereof, which chamber is preferably utilized for the introduction of 75 means for suitably cooling the pier, so as to prevent overheating thereof and possible deterioration due to this cause. This is accomplished by providing the combined steam and air blasting conduit 14 which extends in 80 to the ash pit 4 a suitable distance, with an angular extension 15, which projects upwardly a suitable distance into the chamber 13 of the pier A, and is suitably spaced from the inner walls thereof, so that the blasts 85 of relatively cool air or steam from the conduit 14 are directed upwardly into the chamber 13, and then pass downwardly out of the pier, and upwardly through the grate into the body of fuel supported thereby, 90 the contact of such air or steam with the walls of the pier serving to effectually cool the same. A steam inlet 16 of any suitable construction is also usually provided at the upper portion of the generator for blasting 95 the fuel body in a reverse direction, or downwardly, in a well known manner.

From the preceding description, considered in connection with the drawing, it will be observed that the blasts have equal and 100 uniform accessibility to the bottom of the fuel through all portions of the grate, thus insuring uniform admission of the blasts to the body of the fuel. By proportioning the generator so that the distance between the 105 opposed wall surfaces of the generator and the pier is at no point more than twice the known width of the active area of the fuel with respect to a retaining wall, all portions of the fuel are necessarily arranged 110 within such active area with respect to such walls through the entire mass of fuel from top to bottom. Furthermore, not only are all portions of the fuel located within an active radiating area of a retaining or confining wall, but, in addition, the extension 115 of the central pier well up into the loose or green fuel zone to a point substantially on a level with the offtake, prevents the initiation or formation of any centrally disposed, inert or inactive or impermeable core or mass with the result that the body of fuel, as it gravitates down through the generator from the loose or green fuel zone to the incandescent zone, is distilled and processed 120 uniformly throughout the cross-sectional areas of the body of fuel.

A common size for a generator of circular cross section with a bottom such as indicated in the drawing and hereinbefore 130

described, used in the manufacture of carbureted water gas, is one having an inside diameter of 9 feet. With such a generator, using bituminous coal as the generating fuel, we have found from actual experience, that very efficient results are obtained with our invention where a pier or cone, such as shown in Figure 1 of refractory material is employed of 3 feet outside diameter, centrally disposed on the grate as indicated in the drawing. With such an arrangement, it will be observed that there is no portion of the fuel bed which is more than 18 inches from any radiating wall of the generator, and further, that the blasts of air and steam are over the entire grate-supported area of the fuel bed with equal facility and action at all points, thus assuring uniformity of combustion within the entire body of the fuel. Actual practice has demonstrated that, where air and steam blasts are permitted to enter the body of the fuel through the grate with relative uniformity throughout the entire area supported by the grate, that active zones will be formed within a distance of about 18 to 24 inches of any refractory wall, this active zone being assured by the passage of preheated gases through the fuel or by radiation from the heated refractory surfaces, or by a combination of the two. Consequently, it will be observed that by the use of our invention, all portions of the fuel are brought within an assured active zone of substantially uniform permeability and uniform rate of combustion.

By way of comparison, we have found that the best results obtainable under the prior common practice with a carbureted water gas set, using bituminous coal, the generator of which was 9 feet internal diameter, was by blasting at the rate of 5,000 cubic feet of air per minute, with a resulting capacity of approximately 1,500,000 cubic feet of gas per 24 hours, whereas, by the addition of a pier such as we have shown and described of 3 feet outside diameter, the capacity was increased to 2,500,000 cubic feet of gas per 24 hours, the amount of fuel blown over into the fixing chamber was decreased approximately 50%, the amount of fuel required per 1,000 feet of gas was decreased approximately 8 lbs. and the amount of clinkers formed was materially decreased. By way of a rough approximation, it may be stated that in the generator used without any pier, the active area is that of the annulus having an outside diameter of 9 feet and an inside diameter of 6 feet (that is, 9 feet less two times 18 inches) or approximately 35.3 sq. ft., whereas, by the introduction of the pier of 3 feet, outside diameter, the active area was increased to that within the annulus having a 9 foot outside diameter and a 3 foot inside diameter, or approx-

imately 56.6 sq. ft. that is, an increase of approximately 60% in the active area, and an increase of approximately 67% in the capacity.

We have herein illustrated one apparatus particularly suitable for carrying out our improved process and have described the process with particularity in connection with the apparatus disclosed. As will be understood by those skilled in the art, all changes and modifications that come within the scope of the claims appended hereto, are contemplated. Claims to the apparatus herein illustrated and described are reserved to form the subject matter of a separate divisional application.

We claim:

1. The herein described improvement in the manufacture of a combustible gas from coal of relatively high volatile content, which includes: disposing the fuel in an annular column and confining the same between inner and outer refractory walls with all portions of the fuel of the annular column within an effective radiating distance of the refractory walls and thereby preventing the formation of an impermeable mass or core in the fuel; and blasting the column of fuel in a vertical direction substantially uniformly throughout the area of the annular column of fuel with air and steam alternately.

2. The herein described improvement in the manufacture of a combustible gas from coal, and wherein the body of fuel gravitates through the generator, which consists in: passing blasts of air and blasts of steam through an incandescent fuel bed; and confining the path of movement of all portions of the fuel, during the blasting and processing thereof within a known, substantially uniformly permeable activated area with respect to radiating bounding walls so that formation of inactive masses is thereby prevented, and the entire fuel bed blasted and processed uniformly with minimization of channeling.

3. The herein described improvement in the manufacture of a combustible gas in a generator having an offtake near the top thereof, which includes: confining the path of movement of the fuel, beginning at a point substantially in line with the offtake of the generator, and down into the incandescent zone, into a body whereof all portions of the fuel are within a known, substantially uniformly permeable active area, with respect to radiating wall surfaces by which the path of movement of the fuel is governed; blasting the body of fuel substantially uniformly with air; and passing steam substantially uniformly through the body of fuel whereby initiation of centrally located, substantially impermeable fuel masses or cores are eliminated in the descent

through and from the green or loose fuel zone to the incandescent zone.

4. The herein described improvement in the manufacture of water gas from carbonaceous fuel of relatively high volatile content in a generator wherein the fuel is supported on a grate and the gases are withdrawn from an offtake near the top of the generator which includes: distributing the fuel within the confining walls of the generator from a point substantially in line with the offtake down to the zone of incandescence in such columnar form that all portions of the columnar fuel body are maintained within a known, active area and radiating distance relative to the bounding walls of the columnar fuel body from a point substantially in line with the offtake to the zone of incandescence; blasting the fuel in a vertical direction with air; and, alternately with the air blast, blasting with up and down runs of steam, whereby the columnar fuel body is processed uniformly throughout the sectional areas thereof, channeling minimized, and formation of substantially impermeable masses avoided.

5. In the manufacture of gas with an ignited fuel bed and wherein blasts of air and steam are passed through the fuel bed, the improvement for increasing the output which consists in uniformly distributing the porosity of the fuel bed by co-ordinating the cross sectional area of the fuel bed with its bounding surface, in such a way that, thereby, the formation of inactive fuel masses or cores, which would otherwise be normally formed in the fuel bed during blasting is avoided.

6. The herein described improvement in the manufacture of a combustible gas from solid carbonaceous fuel and wherein the body

of fuel gravitates through the generator, which includes: confining the path of movement of all portions of the fuel during the passage thereof through the zones of distillation and incandescence, within a known, substantially uniformly permeable activated area with respect to radiating wall surfaces by which the path of movement of the fuel is determined; blasting the body of fuel substantially uniformly with air; and passing steam substantially uniformly through the body of fuel whereby the ratio of bounding wall surface to the cross section of the body of fuel is thereby increased, the formation of inactive fuel masses or cores prevented, and uniform processing of the fuel body obtained.

7. The herein described improvement in the manufacture of a combustible gas of the character described from bituminous coal, and wherein the body of fuel gravitates through the generator which consists in: confining the path of movement of all portions of the fuel, during the passage through the zones of distillation and gassification, within a distance of approximately 24 inches or less of a fuel bounding wall; blasting the body of fuel substantially uniformly with steam and with air, the ratio of bounding wall surface to the cross section of the body of fuel being thereby increased, formation of inactive fuel masses or cores prevented, and uniform processing of the fuel bed obtained.

In witness that we claim the foregoing we have hereunto subscribed our names this 16th day of September, 1924.
